UNITED STATES PATENT OFFICE.

HERMAN N. MAY AND ERNEST M. MAY, OF MINERAL POINT, WISCONSIN.

SLIDING DOOR.

Application filed July 28, 1923. Serial No. 654,502.

To all whom it may concern:

Be it known that we, HERMAN N. MAY and ERNEST M. MAY, citizens of the United States, residing at Mineral Point, in the county of Iowa and State of Wisconsin, have invented certain new and useful Improvements in Sliding Doors, of which the following is a specification.

Our invention relates to sliding doors, of the type which are shifted laterally into the door opening, when brought into proximity thereto.

An important object of the invention is to provide a door of the above mentioned character, which is particularly well adapted for use in connection with barns, garages, and other buildings, although the same may be used upon railway cars, or in any other desired place.

20 A further object of the invention is to provide means whereby the door may be opened from either side, and when shifted laterally to the outer position, will be properly guided in its longitudinal travel, retained in close relation to the exterior of the building, or the like.

25 A further object of the invention is to provide means of the above mentioned character, preventing chafing of the door, and eliminating guides or all attachments at the base of the door.

30 A further object of the invention is to provide means for shifting the door laterally into and out of the door opening, and for locking the same in the closed position.

Other objects and advantages of the invention will be apparent during the course of the following description.

In the accompanying drawings forming a part of this specification, and in which like numerals are employed to designate like parts throughout the same,

Figure 1 is an outer side elevation of a door embodying our invention, showing the same in the closed position,

Figure 2 is a transverse sectional view taken on line 2—2 of Figure 1,

Figure 3 is an inner side elevation of the door, showing the same shifted laterally to the open position,

Figure 4 is a transverse section taken on line 4—4 of Figure 3,

Figure 5 is a perspective view of the shifting and locking means,

Figure 6 is a transverse sectional view 65 through the angle bar or guide element, showing it in the upper position,

Figure 7 is a similar view showing the same in the lowered position, and,

Figure 8 is a horizontal section on line 80 8—8 of Figure 3.

In the drawings, wherein for the purpose of illustration is shown a preferred embodiment of our invention, the numeral 10 designates a wall, having a door opening 11 65 formed therein. This wall may be regarded as a portion of a barn, garage, or car body.

The numeral 12 designates a sliding door, adapted to be shifted in front of the door opening, in registration therewith, and then 70 shifted laterally to enter the door opening, and to fit snugly therein. The door 12 is provided with recesses 13, upon its outer face, for the reception of brackets 14 secured therein by bolts 13', secured to the 75 door and passing through openings in the brackets 14. These brackets receive between them the lateral ends 15 of suspension arms 16. The lateral ends are pivotally connected with the brackets, as are shown at 17. The 80 suspension arms 16 are provided at their upper ends with lateral extensions 18, pivotally connected at 19, with depending hangers 20. These hangers are secured to carriages 21, equipped at their ends with pairs 85 of wheels 22, traveling within an enclosed track or guide-way 23. This enclosed track is bolted or otherwise rigidly secured to the wall 10, above and adjacent to the door opening, as shown. From the foregoing de- 90 scription, it will be seen that the door may be shifted laterally into the door opening 11, Figure 2, or it may be shifted outwardly, and will hang substantially perpendicular as indicated in Figure 4, whereby it will 95 slide longitudinally in close relation to the wall 10.

Means are provided for effecting the lateral movement of the door, embodying an angle iron or bar 24. The bar 24 is 100 L-shaped in cross-section and is horizontally arranged upon the inner side of the door. At its ends, Figure 5, the angle iron 24 has pivot elements or shafts 26 and 27, rigidly attached thereto, at its turning edge. 105 This edge of the angle iron is secured to the inner side of the door by means of a hinge 28 or the like. It is thus seen that the

elements 26 and 27 serve as pivotal supporting means for the angle iron, and that this angle iron also serves to cause these pivot elements to turn in unison. The angle iron also serves as a wear strip in the longitudinal travel of the door. The shaft 26 is pivotally mounted within a bearing 29, formed upon a plate 30, which is bolted to the inner side of the door. The shaft 26 is continued beyond this bearing in the form of a laterally extending crank 31, provided with a curved portion 32 having an extension 33, arranged at a right angle thereto, carrying a roller 34, for a purpose to be described. The shaft 27 is pivotally mounted within a bearing 35, formed upon a plate 36, which is bolted to the inner side of the door. This plate carries an upstanding portion 37, as shown. The shaft 27 is continued beyond the bearing 35 in the form of a crank 38, having a curved portion or neck 39, carrying an extension 40, at a right angle thereto, upon which is rotatably mounted a roller 41. The cranks 31 and 38 project outwardly beyond the door through vertical slots 42 and 43, and the inner sides of these slots are covered by guard plates 44 and 45, as shown. The roller 34 is adapted to engage within a bracket 46, the upper end of which is open and which is provided in its bottom with a cylindrical portion 47, for rotatably receiving the roller. The bracket 46 is carried by a plate 48, bolted or otherwise rigidly secured to the door jamb, at the right end of the door opening. The roller 41 is adapted to enter a bracket 49, having cylindrical portions 50 and 51, for freely receiving the roller. The walls of the bracket 49 are spaced apart sufficiently to allow the roller 41 to pass from the portion 51 to the portion 50. This bracket is carried by a plate 51, bolted or otherwise rigidly secured to the left door jamb, Figure 1. The bracket 49 also carries a resilient guard 52, curved outwardly slightly, to engage with the roller 41 and shift the same inwardly, into the bracket 49, when the door is shifted to the closed position, Figure 1.

Means are provided to turn the angle bar 24 upon its longitudinal axis, embodying a pair of levers 52', rigidly attached to the angle bar at 53. These levers operate through slots 54 in the door. Upon the inner side of the door, the levers are substantially straight, and are connected by a handle 55, and the outer ends of the levers are preferably bent at a right angle, and are equipped with a handle 56, connecting them. If desired, the outer end of the levers may be locked in the closed position, and for this reason one lever may be passed between a pair of brackets 57, apertured for receiving the hasp of a pad lock or the like.

The plate 48, to the right, is provided

with a guide bracket 58, which is in alignment with the angle bar 24, when it is swung downwardly, Figure 7, and the door shifted outwardly, Figure 4. Upon the longitudinal movement of the door, the then vertical web of the angle iron will slide into the guide bracket 58, and hence the door will be retained in close relation to the wall. If desired, any suitable number of brackets 58 might be arranged in horizontal alignment along the exterior of the wall, to receive the angle iron.

The operation of the apparatus is as follows:

When the exterior handle 56 is in the raised position, the rollers 34 and 41 are in the elevated position, and the cranks 31 and 38 are raised, Figure 4. These cranks have forced the door outwardly, to the position shown in Figure 4, and the door may now slide longitudinally. The curved ends of the cranks will permit the cranks clearing the bracket 46. As the door is shifted longitudinally to the open position, the then vertical web of the angle iron 24 will slide within the guide bracket or brackets 58. The door may be shifted longitudinally to the closed position, and when it is brought into alignment to the door opening, the handle 56 is forced downwardly. This movement swings the cranks 31 and 38 to the horizontal position, Figure 2, and by virtue of their engagement within their brackets, the door is shifted inwardly, to enter the door opening. The angle bar serves to connect the two cranks, causing them to move in unison.

It is to be understood that the form of our invention herewith shown and described is to be taken as a preferred example of the same, and that various changes in the shape, size, and arrangement of parts may be resorted to without departing from the spirit of our invention, or the scope of the subjoined claims.

Having thus described our invention, we claim:

1. A sliding door adapted to be shifted laterally into a door opening in a wall, a track supported near the door opening and extending longitudinally thereof, rollers traveling upon the track, hanger arms pivotally connected with the rollers and door to permit the door to swing laterally upon entering the door opening, an angle bar pivotally mounted upon the inner side of the door, means to turn the angle bar upon its longitudinal axis, cranks connected with the ends of the angle bar and projecting upon the outer side of the door and having curved necks, rollers pivotally connected with the necks and projecting laterally therefrom, brackets secured to the outer side of the wall near the door opening and adapted to receive the last-mentioned rollers therein, said

necks clearing one bracket upon the longitudinal movement of the door, and a guide bracket secured to the outer side of the wall to receive one web of the angle bar, upon 5 the longitudinal movement of the door.

2. A sliding door adapted to be shifted laterally into a door opening in a wall, a track supported near the door opening and extending longitudinally thereof, rollers 10 traveling upon the track, means supporting the door upon the rollers to permit the door to be shifted laterally into the door opening, an angle bar pivotally mounted upon the inner side of the door, means to turn the angle 15 bar upon its longitudinal axis, cranks connected with the angle bar to be turned thereby and projecting upon the outer side of the door, rollers pivotally connected with the cranks, brackets secured to the outer side 20 of the wall near the door opening and adapted to receive the last-mentioned rollers therein, and a guide bracket secured to the outer side of the wall to receive one web of the angle bar, upon the longitudinal movement 25 of the door.

3. A sliding door adapted to be shifted laterally into a door opening in a wall, a track supported near the door opening and extending longitudinally thereof, rollers 30 traveling upon the track, means supporting the door from the rollers to permit the door to be shifted laterally into the door opening, an angle bar extending longitudinally of the door and pivoted thereto, handles connected with the angle bar to turn it upon 35 its longitudinal axis and projecting upon opposite sides of the door, cranks connected

with the angle bar to turn therewith and projecting laterally beyond the door and having curved necks, rollers connected with 40 the necks and arranged at an angle thereto, brackets secured to the wall near the door opening for receiving said last-mentioned rollers, said curved necks clearing one of the 45 brackets upon the longitudinal movement of the door, and a guide bracket secured to the wall for receiving a web of the angle iron, upon the longitudinal movement of the door.

4. A sliding door adapted to be shifted laterally into a door opening in a wall, a track supported near the door opening and extending longitudinally thereof, rollers traveling upon the track, means supporting the door from the rollers to permit the door to be shifted laterally into the door opening, a supporting element pivotally mounted 50 upon the inner side of the door and extending longitudinally thereof, means to turn the supporting element upon its longitudinal axis, cranks carried by the supporting element and projecting to the outside of the door and provided at their ends with curved necks, rollers pivotally mounted upon the curved necks and arranged at an angle 55 with relation thereto, and brackets secured to the outer side of the wall to receive said last-mentioned rollers, said curved necks clearing one bracket upon the longitudinal movement of the door.

In testimony whereof we affix our signatures. 70
